2 Claims. (Cl. 126—120)

1

The present invention relates to a fireplace construction and more specifically pertains to open fireplace installations.

Open fireplace installations are known in which the combustion air supplied to the underside of the grate is derived entirely from outside the room to be heated by the fire, for example from under the floor. Such an arrangement, as compared with an open fireplace in which the air for combustion is drawn from inside the room, enables a greater pressure differential across the fuel bed to be obtained. This increased pressure differential can be utilised both to obtain a more rapid stimulation of combustion and to attain a higher rate of combustion.

In the known open fireplace installations of the aforesaid kind, a damper is provided which is intended to control the supply of the air admitted to the underside of the grate from outside the room. It is difficult, however, to control the rate of combustion satisfactorily by this means alone. Owing to the relatively high pressure differential across the fuel bed the velocity of the air increases as the damper opening is reduced, and hence the quantity of air admitted in unit time is not reduced in proportion to the reduction in the opening. Only when the damper is very nearly closed will there be any real reduction in the quantity of air admitted so that it is only possible to obtain any useful variation in the air supply over a very small range of operation of the damper in the vicinity of its closed position.

It is an object of the present invention to provide a more satisfactory control over the rate of combustion.

According to this invention an open fireplace installation comprises, air supply means for the supply of air for combustion from outside the room to be heated by the fire, a grate the underside of which receives combustion air entirely from the said air supply means, a chimney disposed above the grate for the removal of products of combustion, a member having an outlet communicating with the said air supply means and so situated near the grate as to enable air from the said air supply means to pass into the room and thence into the chimney, and valve means provided in the said air supply means for varying the supply of air to the underside of the grate and to said outlet in such manner that when the supply of air to the underside of the grate is reduced the supply of air to the said outlet is increased and vice versa.

In an installation according to the invention when the valve means, for example a damper,

2

is operated for the purpose of reducing the supply of air to the underside of the grate an increase in the flow of air through the outlet occurs and this causes a reduction in the pressure differential across the fuel bed; and conversely when the damper or like means is operated for the purpose of increasing the supply of air to the underside of the grate a reduction in the flow of air through the outlet occurs causing an increase in the pressure differential across the fuel bed.

Owing to the variation in the pressure differential which accompanies the operation of the valve means a more satisfactory control of the quantity of air admitted to the underside of the grate, and consequently of the rate of combustion, is obtained.

The outlet to enable air from the said air supply means to pass into the room and thence into the chimney may advantageously be situated in front of and near the grate.

The air may be derived from outside the room in any suitable manner, but it is generally more convenient to derive it from the space beneath the floor of the room.

The invention is illustrated in the accompanying drawings, in which Figure 1 shows a vertical cross sectional view of one construction of open fireplace installation in accordance with the invention, and Figure 2 is a similar view of the same construction drawn on a smaller scale to include the chimney.

The fireplace installation shown in the drawings has a hearth 1 raised above the level of the floor 2. The grate 3 is situated at about the level of the hearth, and an outlet is provided in the hearth in the form of an opening in which is supported a removable cover plate 4 provided with a grille or louvred opening 4a to permit air to pass through the plate 4 from beneath the floor. A cavity or chamber 5 is provided beneath the fireplace extending from the back of the grate to the front edge of the opening in the hearth. An opening 6 to admit air from beneath the floor is provided at the top of the front wall 7 of the cavity 5.

At the rear edge of the plate 4 is pivoted at 8 a damper plate 9 extending beneath the grille or louvred opening 4a. The damper plate 9 is adapted in its lowermost position to close an inlet 10 in an inclined frame 11, which frame shuts off communication between the cavity 5 and the opening 6 except through the inlet 10. In its uppermost position the upper surface of the damper plate 9 rests against the underside of the cover plate 4 and closes the louvred opening 4a.

The movement of the damper plate 9 is controlled by the rotation of a knob 12 fixed to a spindle 13 rotatably mounted in a boss 14 on the plate 4. At its lower end the spindle 13 carries a lug 15 upon which rests a helical ramp 16 on the underside of the damper plate 9. The pitch of the ramp 16 is such that a single revolution of the spindle 13 and its lug 15 will suffice to move the damper plate 9 from either of its extreme positions to the other, and that the damper plate will be held in any intermediate position by the lug. In the lowermost position of the damper plate the air supply from the opening 6 to the cavity 5 and underside of the grate 3 is shut off, and the air supply from the opening 6 to the louvred opening 4a fully open. Conversely, in the uppermost position of the damper plate 9 the air supply to the louvred opening 4a is shut off, and the air supply to the cavity 5 and grate 3 is fully open. At intermediate positions of the damper plate 9 a part of the air from the opening 6 passes to the cavity 5 and grate 3 and a part to the louvred opening 4a.

The cavity 5 accommodates an ash receiver 17 disposed beneath the grate. The capacity of the ash receiver is preferably sufficiently large to receive the ash produced by the fire over a period of several days, for example a week. When it is necessary to empty the ash receiver, the plate 4 covering the opening in the hearth is removed, and the ash receiver is then moved forwards beneath the inlet 10 and lifted through it and through the opening in the hearth.

The rate of combustion of the fire is controlled by manipulating the damper plate 9. When the latter is in its uppermost position all or substantially all the air drawn through the opening 6 from outside the room passes through the inlet 10 and to the underside of the grate, and full advantage is taken of the high pressure differential thus obtained. In consequence the stimulation of combustion is very rapid and combustion can attain a very high rate. For example, in a fireplace of average size a rate of combustion as high as 8 lbs. of bituminous coal per hour can be attained as compared with a rate of 4 lbs. per hour in the case of an ordinary open fire.

It will, however, seldom be desired to maintain high rates of combustion for long periods, so that the uppermost position of the damper plate 9 will generally be used only to produce rapid acceleration of combustion. When the damper plate is in its lowermost position all or substantially all the air drawn through the opening 6 from outside the room passes through the louvred opening 4a in the hearth into the room and thence into the chimney 18, and the rate of combustion is then reduced to its lowest level, for example, to about 1 lb. of coal per hour or less. In order to adjust the rate of combustion to a value between these two extremes the damper plate is set at an intermediate position at which the ratio of the air passing to the underside of the grate 3 to the air passing through the louvred opening 4a in the hearth is such as to give the desired rate of combustion.

With an open fireplace installation constructed in accordance with the invention it is possible to burn satisfactorily fuels such as anthracite and coke, which are difficult to burn alone in an open fireplace in which the air for combustion is drawn from within the room. For the same reason it is possible to burn bituminous coal of small sizes which, owing to their slow combustion rate, are

not usually regarded as suitable for open fire-places of the ordinary type.

A further advantage of an open fireplace installation constructed in accordance with the invention is that it becomes possible, at medium rates of combustion, materially to reduce the quantity of air drawn into the room through doors, windows or other apertures.

It will be understood that the invention may be applied to open fireplace installations having associated therewith an appliance heated by the fire, such as a boiler or cooking oven.

Owing to the rapid acceleration in the rate of combustion obtainable in an open fireplace installation in accordance with the invention, the time taken, when the fire is initially lighted or when the fire is refuelled, for the fuel bed to reach a sufficiently high temperature to enable the volatile products such as smoke to be burned is considerably reduced as compared with the time required in an ordinary open fire.

We claim:

1. An open fireplace installation comprising, air supply means for the supply of air for combustion from outside the room to be heated by the fire, a grate the underside of which receives combustion air entirely from the said air supply means, a chimney disposed above the grate for the removal of products of combustion, a member having an outlet communicating with the said air supply means and so situated in front of and near the grate as to enable air from the said air supply means to pass into the room and thence into the chimney, and valve means provided in the said air supply means for varying the supply of air to the underside of the grate and to said outlet in such manner that when the supply of air to the underside of the grate is reduced the supply of air to the said outlet is increased and vice versa.

2. An open fireplace installation comprising, a grate, a chimney disposed above the grate, air supply means for the supply of air for combustion from a space beneath the floor of the room to be heated by the fire, a member having an outlet situated in front of and near the grate to admit air from the said air supply means into the said room and thence into the chimney, side and bottom walls forming below the floor of the said room a chamber having at the front part of the top thereof beneath the said outlet member an inlet to admit air to the chamber from the said air supply means, the said grate being mounted over the rear part of the top of the said chamber so that the underside of the grate receives combustion air entirely from the said chamber, and a damper plate adjustably mounted between the said inlet and outlet for varying the supply of air thereto in such manner that when the supply to the inlet is reduced the supply to the outlet is increased and vice versa.
